(57) CLAIM

I claim the ornamental design for a lamp for bikes, as shown and described.

DESCRIPTION

FIG. 1 is a perspective view of a lamp for bikes, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a perspective view showing the claimed design attached to a clip.

The broken line showing of the clip is included for the purpose of illustrating environmental subject matter and forms no part of the claim.

1 Claim, 8 Drawing Sheets
